CALCULATING MACHINE

Leroy J. Sampson, Detroit, Mich., assignor to
 Burroughs Adding Machine Company, Detroit,
 Mich., a corporation of Michigan

Application July 11, 1934, Serial No. 734,570

4 Claims. (Cl. 235—60)

This invention relates to a calculating machine. It is directed primarily to the provision of an improved construction for counting predetermined items entered in said machine.

5 Item counters have heretofore been produced which operate to count certain items entered in a machine, but they are usually distinct counters that are added to the calculating machine for the express purpose of counting items. They 10 constitute special additions or attachments to the regular mechanism.

The present invention concerns an improvement that enables one of the regular registers to be used for item counting purposes by a few 15 simple changes and without the addition of special counting mechanism.

The general object of the invention is to provide an improved item counting construction for calculating machines.

20 A more particular object is to provide a construction whereby a regular register of a calculating machine may be used for item counting purposes.

A further object is to provide an item counting construction in which the item counter may 25 be charged with a given number at the same time that an item is entered in the machine.

Other and more particular objects will appear from the following specification and drawing.

30 An embodiment of the invention is shown in the accompanying drawing in which;

Figure 1 is a partial right sectional elevation of a machine with the invention applied thereto, the parts being shown in normal position.

35 Fig. 2 is a separated perspective of four banks or columns of the machine with the invention applied thereto.

The invention is shown applied to a Burroughs Class 4 duplex calculating machine whose construction is well known as the machine has been 40 on the market for a number of years. It is to be understood, however, that the invention can be used on other calculating machines and the embodiment illustrated herein is merely by 45 way of example.

General features of machine.

The machine is provided with a plurality of horizontally movable index bars 10 each of which 50 carries upper and lower rack plates 11 and 12. The number of these bars may be varied to suit the requirements, but there are usually nine, that is, the machine has nine orders or banks. For 55 the purpose of this description we will call the index bars with their rack plates, actuator racks.

The actuator racks move to differential positions which are determined by item entering devices comprising depressible amount keys 13. The stems 14 of these keys project into the paths of lugs 15 on the bars 10. After the keys have 5 been depressed, the machine is given a cycle of operation during which the actuator racks are released for movement to differential positions. In some machines the racks are moved to differential positions by hand as in a lever-set machine, or their position may be determined by stop pins set up in a ten key machine or by means of devices controlled by perforated cards. The invention is equally effective with any of 10 these different constructions for determining the positions of the racks. The actuator racks and the devices for controlling their differential positions constitute what will be called "amount determining differential devices."

The rack plates 11 and 12 are slidably mounted 20 by a pin and slot connection on their respective bars 10 and each is urged by a spring 16 toward the right as viewed in Fig. 1.

An upper register carried by the shaft 20 and a lower register carried by the shaft 21 are associated with the actuator racks. The racks and registers are mounted to enable a relative movement to occur between them for engagement and disengagement. In this case the registers are moved to and from the racks as will be later described.

Suitable control keys are provided including 25 keys for placing either or both registers in non-add condition and for taking a total or sub-total from either register. It is possible to take a 30 total from one register while the other remains in add condition so that the total in one is transferred to the other, but it has not been considered necessary to show these controls in the present case.

40 The machine is also provided with a suitable paper carriage and a printing mechanism with provisions for splitting the same at desired points. The machine is given cycles of operation by a handle or motor, but it has not been considered necessary to illustrate any of these parts.

Suitable carriage controls are provided so that, in certain columnar positions of the carriage, either or both of the registers may be conditioned 45 for addition or for non-adding.

50 When the machine is given a cycle of operation after the amount keys have been depressed, the actuator racks are released for movement to differential positions which are determined by the depressed amount keys. After these racks 55

have been positioned either or both of the registers are rocked into engagement with them and the racks are then restored to normal. During the restoration of the racks to normal the amount entered on the keys is registered in the register mechanism or mechanisms that engage the racks. Totals and sub-totals are taken by changing the time of engagement and disengagement of the registers with the racks.

10

Lower register

The lower register comprises a plurality of register pinions 22 mounted loosely on the shaft 21. This shaft is carried by arms 23 journaled on a shaft 24 supported by the frame plates of the machine. The free ends of the arms are joined by a cross member 25 which, together with the arms 23 forms a register supporting frame. The register frame is urged clockwise as viewed in Fig. 1 by a spring 26 so that the lower register is urged out of engagement with the actuator racks. The register is, however, normally held in engagement with the racks by means of a cam arm 27 pivoted at 28 and provided with a hooked end 29 engaging under a stud 30 on an arm 31 which is integral with one of the side arms 23 of the register frame. In addition, as the machine starts to operate, the cam arm 27 is rocked counterclockwise as viewed in Fig. 1, to release the stud 30 whereupon the spring 26 moves the register out of engagement with the racks before they start to move. After the racks have been differentially positioned, the cam arm 27 is returned clockwise and its cam end engages the stud 30 and moves the arm 31 counterclockwise as viewed in Fig. 1 to engage the register with the racks prior to the restoration of the latter to normal. The movements of the cam arm 27 are controlled by a non-add key, a total key and the paper carriage, but since these controls are known, they will not be described.

Tens transfer mechanism

Except as hereinafter described, the tens transfer mechanism for the upper and lower registers is the same and the description will be confined to one, namely, the tens transfer mechanism for the lower register.

Each of the rack plates 11 and 12, except those in the units order, is provided with a stud 40 adapted to be engaged by the nose of a pawl 41. As previously explained, these rack plates are urged to the right as viewed in Fig. 1 by the springs 46. But the pawls 41 are positioned so that, when the parts are in the normal position of Fig. 1, the rack plates are held one step away from their extreme right hand position relative to the bars 10. As the actuator racks are moved to the left in Fig. 1 to their differential positions, which occurs during the first part of the cycle of operation of the machine, the studs 40 move away from the pawls 41 and the rack plates are free to be moved to their extreme right hand positions relative to the bars 10. Upon the return of the racks to normal the studs 40 engage the pawls 41 and, if these pawls are held in the positions shown in Fig. 1, the racks are arrested one step short of their extreme right hand position. The bars 10 continue to the full extent of their movement.

The tens transfer is controlled by controlling the pawls 41, that is, the pawl 41 that engages the stud 40 of a rack in a particular order is controlled by the pinion of next lower order and the arrangement is such that, if a tens transfer

is to occur in a particular order, the pawl for the next higher order is released so that its rack can continue to the full extent of its right hand movement and cause an extra step of movement of its register pinion.

For the purpose of controlling the tens transfer pawls 41 each pinion of the registering mechanism is provided with a snail cam 42 (Fig. 2) adapted to cooperate with a lateral lug 43 on a latch 44 pivoted at 45. The other end of this latch has a lateral lug 46 engaging over a shoulder 47 on the lower end of the pawl 41.

When the register pinion of a given order moves from its "9" to, or through, its "0" position, the snail cam 42 for that pinion trips its latch 44, that is, moves it clockwise as viewed in Fig. 2. This moves lug 46 forwardly and releases the pawl 41 of the next higher order for movement in a clockwise direction. The result is that, when the rack of the next higher order is restored to its normal position, the pawl 41 for that order no longer blocks the rack plate 12 and the rack plate moves an extra step to cause a tens transfer.

This construction is duplicated between each of the orders of the registering mechanism and no further description seems necessary. It is to be understood that a suitable restoring mechanism is provided for restoring the parts to normal.

Upper registering mechanism

The upper registering mechanism is similar to the lower register. It comprises a plurality of register pinions 50 mounted on the shaft 20 carried by arms 51 joined by cross bar 52 forming a register frame pivoted on the shaft 53. This register frame is normally urged counterclockwise in Fig. 1 by a spring 54 that is connected to an arm 55 integral with one of the side arms 51 of the register frame. The register is thus urged out of engagement with the actuator racks. It is normally held in engagement, however, by a cam arm 56 engaging over a stud 57 on the arm 55.

In adding operations, as the machine starts to operate, the cam plate 56 is moved counterclockwise from its position in Fig. 1 which releases the upper register so that it is moved out of engagement with the actuator racks by the spring 54. The racks are then differentially positioned after which the cam 56 is moved clockwise to cam the register into engagement with the racks prior to their return to normal.

The tens transfer mechanism for the upper register is exactly like that for the lower register except as hereinafter described.

Item counting mechanism

In the embodiment shown the upper registering mechanism is used as an item counting register and certain modifications are made in it as follows:

The pinions of the upper registering mechanism are divided into two groups, those on the left hand side, viewing the machine from the front, being used to accumulate or count the items, and those on the right being used to effect the counting. The number of pinions in each group may be varied to suit the requirements. Usually the first two or three pinions on the left are used for item counting and the remaining six or seven pinions on the right are employed to effect the item counting. In Fig. 2 of the drawing only four of the register pinions have

been illustrated and, in this figure, the two pinions on the left count the items while the two pinions on the right effect the item counting, the other pinions having been omitted to avoid 5 confusion.

The pinions of the left hand group have a tens transfer mechanism associated with them exactly like that heretofore described so that a transfer occurs from one order to the other when 10 the pinion of a given order passes from its "9" to or through its "0" position. These register pinions cooperate with the rack bars of their orders and suitable banks of keys are provided to control the racks in the usual manner.

15 The right hand section of the registering mechanism is modified to adapt the registering mechanism for item counting. Instead of having a snail cam associated with each register pinion to effect a tens carry, a ten-tooth disk 20 60 is associated with each register pinion. These disks cooperate with the lateral lugs 48 of the transfer latches 44 heretofore described. With this arrangement, whenever any of the pinions of the right hand section move a single step, 25 the corresponding transfer pawl 41 is tripped so as to cause a transfer into the next higher order. The transfer into the next higher order causes one step of movement of the next higher order pinion and the disk 60 for that pinion then causes 30 a transfer to the next higher pinion, and so on across the entire right hand group of register pinions. The transfer from the left hand pinion of the right hand group causes the right hand pinion of the left hand group to move a 35 step, but the left hand group has the regular tens transfer mechanism associated with it and hence this one step of movement of the right hand pinion of the left hand group does not cause a tens transfer but merely enters a unit 40 in the item counting section of the registering mechanism.

It will be immediately appreciated that the substitution of the disks 60 for the snail cams in the right hand group of register pinions 45 constitutes a small change in the mechanism. The change can be simply and easily made without great expense. But the results achieved are very great and quite unexpected. They enable the upper registering mechanism to be used for 50 item counting purposes with a degree of flexibility that is very desirable.

For example, no matter what the amount of an item is, the item counter will be moved only one unit for that particular item. The item may 55 be one cent, or it may be a multiple digit figure such as \$1,264.75.

If the item is one cent, the rack in the cents order moves one step. This causes the units pinion to move a step and the movement of this 60 pinion causes a transfer across all the pinions of the right hand group and the entry of one unit into the left hand group.

If the item is \$1,264.75, a rack moves in each 65 of the item entering banks and the racks move different extents. But only one unit is transferred from the right hand group of pinions to the left group because, as soon as the transfer mechanism operates, it remains in its operated condition and cannot be operated a second time 70 during that cycle of machine operation. It must be restored before another unit can be transmitted.

The entry of this unit in the item counter occurs at the same time that the item is being 75 entered in the lower register and requires no at-

tention on the part of the operator. All that he needs to do is enter the item in the machine.

If a plurality of items are entered and it is desired to count each one of them, the upper registering mechanism is moved into engagement 5 with the racks for each item. If a plurality of items are entered but it is desired to count only one of them, the upper registering mechanism is engaged with the racks during entry of only one item. This engagement may be caused automatically by means of the paper carriage in a predetermined column, or it may be caused manually by the depression of a key or any other manipulative member.

When a total is taken from the lower register 15 the upper registering mechanism cannot be engaged with the racks so that no item is counted during a total taking operation from the lower register.

If it is desired to charge the item counter with 20 a given number before starting operations, this can be done by entering the amount on the keys of the left hand banks. The operator need not give the machine a stroke of operation for charging the item counter. He can go right 25 ahead and enter the item that is to go into the lower register. Then, during the cycle of operation of the machine, the item counter will be charged with the number that has been entered on the keys of its orders, the items to be entered in the lower register will be simultaneously added to the latter, and while this is taking place, the item entered in the lower register is counted by reason of the fact that the right hand group 30 of pinions of the upper registering mechanism will cause a unit to be introduced into the item counter. In other words, the item counter can be charged and an item can be simultaneously entered in the machine and counted.

When it is desired to print the amount in the 35 item counter and clear it, a total is taken from the upper registering mechanism. It will be apparent that the pinions of the right hand group of the upper registering mechanism will prevent any movement of the actuator racks during total taking and hence the type bars for these orders remain in zero position. In order to prevent the printing of zeros to the right of the left hand or item counter orders, the printing mechanism is 40 split between the left and right hand groups of pinions of the upper register. The item counter 45 can be cleared without printing by blocking the printing mechanism.

When it is desired to print the amount in the 50 item counter and to leave said amount in the counter, a sub-total is taken from the upper registering mechanism.

It is to be understood that the construction 55 shown is for purposes of illustration only and that variations may be made in it without departing from the spirit and scope of the invention 60 as defined by the appended claims.

I claim:

1. A calculating machine having a plurality of 65 orders of amount determining differential devices, a registering mechanism having a plurality of orders corresponding to the orders of said devices, said registering mechanism and devices being adapted for engagement with one another, means for causing such engagement, and means operatively connected with and operable by a predetermined number of orders of said registering mechanism for causing a unit to be entered in the remaining portion of said registering mechanism when any of said predetermined orders of said 70 75

registering mechanism is moved, a single unit only being entered irrespective of which or how many of said predetermined orders of said registering mechanism is moved and the amount of its or their movement.

2. A calculating machine having a plurality of actuator racks, means for limiting the movement of said racks in differential positions in accordance with items entered in the machine, a registering mechanism adapted to engage and disengage said racks, said registering mechanism having a plurality of pinions corresponding to said racks, which pinions are divided into two groups, means for engaging and disengaging said registering mechanism and racks, and means operable by one group of pinions causing a unit to be entered in the other group whenever any of the pinions of the first group are moved, a single unit only being entered irrespective of which pinion or pinions of the first group is moved and the extent of its or their movement.

3. A calculating machine having a plurality of actuator racks, item entering means for limiting the movement of said racks in differential positions, a registering mechanism adapted to be engaged with and disengaged from said racks, said registering mechanism having a plurality of pinions divided into two groups, a tens-transfer mechanism associated with one group of said pinions,

and a transfer mechanism associated with the other group of said pinions arranged for operation on one step of movement of each of said pinions whereby, when said registering mechanism is engaged with said racks, the movement of any or all of the racks associated with said second group of pinions will cause a unit to be entered in the first group of pinions irrespective of the extent of movement of said racks.

4. A calculating machine having a plurality of actuator racks, item entering means for limiting the movement of said racks in differential positions, a register associated with said racks to receive the items, a registering mechanism associated with said racks, said registering mechanism having a plurality of register pinions divided into two groups, a tens-transfer mechanism associated with the pinions of one group, a transfer mechanism associated with the pinions of the other group which pinions cooperate with the racks employed for item entering, said transfer mechanism being adapted to operate for each step of movement of any pinion of its group whereby, when an item is entered in said register, a unit will be entered in said first group of pinions of said registering mechanism irrespective of what the item may be.
